(57) CLAIM

The ornamental design for a spray gun for kitchen, as shown.

DESCRIPTION

FIG. 1 is a perspective view of a spray gun for kitchen showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings are for the purpose of illustrating portions of the spray gun for kitchen that form no part of the claimed design.
